UNITED STATES PATENT OFFICE

ALONZO F. KERNS, OF CHICAGO, ILLINOIS.

HORSESHOE.

SPECIFICATION forming part of Letters Patent No. 714,380, dated November 25, 1902.
Application filed March 28, 1902. Serial No. 100,358. (No model.)

To all whom it may concern:

Be it known that I, ALONZO F. KERNS, of Chicago, in the county of Cook and State of Illinois, have invented in certain new and useful Improvements in Horseshoes; and I do hereby declare that the following is a full, clear, and exact description of the invention thereof, reference being had to the accompanying drawings, and to the letters of reference marked ¹⁰ thereon, which form a part of this specification.

This invention relates to certain new and useful improvements in cushion or soft-tread horseshoes, in which the tread of the shoe is formed by a body of yielding material, such as rubber, which is removably secured to the metal body of the shoe, whereby said tread-body may be removed as it becomes worn or otherwise incapacitated, and replaced by a new or perfect tread-body; and the invention ²⁰ consists in the matters hereinafter set forth, and more particularly pointed out in the appended claims.

The invention relates to the means for fastening the tread-body to the shoe and to general features of construction of the shoe.

Among the objects of my invention is to provide a cushioned or soft-tread horseshoe of the character described wherein the cushion or tread-body may be readily removed from or attached to the shoe while the shoe is on the horse, thereby rendering it unnecessary that the shoe be removed for replacing a worn-out tread.

As shown in the drawings, Figure 1 is a bottom plan view, partially broken away, of a cushion or soft-tread horseshoe made in accordance with my invention. Fig. 2 is a cross-section thereof, taken on the indirect line 2-2 of Fig. 1. Fig. 3 is a similar section of a plate-shoe, showing my improved cushion-tread attached thereto.

As shown in the drawings, A designates the body of the shoe, which is provided on its under side with a groove A', extending from one end thereof to the other and formed between inner and outer flanges A² A³ at the margin of the shoe. Said shoe-body is provided within said recess with nail-holes a, through which are passed the nails by which the shoe is secured to the foot of the horse. The outer flange A³ is somewhat thickened at

the toe of the shoe to provide the usual toe-weight.

B designates the cushion-tread of the shoe, ⁵ which consists of a narrow strip or body of suitable yielding material, such as rubber, and is seated in said recess A'. Said tread-body is made of sufficient width and length as to completely fill said recess and is made considerably thicker than the depth of the recess, whereby it extends some distance below or beyond the flanges A² A³ of the shoe body for contact with the roadway. The contact-surface of the full width of the body is ¹⁵ flat and of the maximum holding-surface that may be given a maximum holding-surface is the side walls of the recess A' are straight and parallel, if desire to. The side walls of the recess A' are as made straight and parallel, if desire not sufficiently to interfere with the in- of the tread-body in the top of the recess.

Embedded in the top of the recess, in that part thereof which is contained in the recess A' are two stiffening-wires which extend from end to end of the body and are located side by side in a plane. Said wires are placed in the body when the latter is molded or formed.

D D designate the tread-body stiffening-wires C and have screw connection with the web of the shoe. Said screws are provided with flat heads D', which overlap wires C C in a manner clearly 2, and when said screws are ²⁰ driven into place and are the with the shoe-body the head said wires in a manner to be forced out of the shoe-body.

The tread-body is provided with openings through which are passed when inserted the screw-heads. The screws are seated in the screw-holes being made of slightly larger diameter than the screw-heads. The screws are filled with like-sha- the same material as the screw-plugs are secured in the material of the fillin substantially the same of the tread-body.

The usual manner, and thereafter the rubber tread is inserted in the recess and fastened 5 therein by means of the screws D. Thereafter the plugs B² are inserted into the screw-openings to cover the screws and afford a continuous or unbroken contact-surface to the tread-body. When the tread-body wears away, which will occur before it is necessary to reset the shoe, the tread-body may be removed by first baring the screw-heads D, after which thereafter removing the screws D, after which the tread-body may be readily removed and 15 a new one substituted therefor in a manner before described.

In Fig. 3 I have shown the manner of applying my improved tread-body to a plate-shoe the bottom surface of which is flat. As shown in said figure, E designates the shoe, and F the tread-body. Said tread-body is made substantially like that heretofore described, having embedded therein longitudinal stiffening-wires F' F', and screws G, which have screw-threaded connection with the shoe-body, extend through openings in the tread-body located between said wires F' to hold the screw-heads in place. The openings through which overlap the wires F' are passed, and the heads of the screws are held by plugs f in a manner like that here-described.

The shoe shown in Fig. 3 is designed more especially for use on high-bred horses, such as horses, during transportation from place, and it is proposed to provide e or track shoes of the horses with such as thereto just before shipping the

It may be made in the structural details departing from the spirit of my and I do not wish to be limited to such details except as hereinafter object of specific claims.

My invention—

A elastic tread horseshoe comprising a elastic tread applied to the

under side thereof, longitudinal stiffening-wires embedded side by side in the tread-body, screws extending upwardly through the web of the shoe-body and heads on the web which have overlapping engagement with said wires.

2. An elastic-tread horseshoe comprising a metal body having a downwardly-opening recess, an elastic tread seated in said recess, longitudinal stiffening-wires embedded side by side in the tread-body, screws extending upwardly through said tread-body and heads on the screws which have overlapping engagement with said wires.

3. An elastic-tread horseshoe comprising a metal body, an elastic tread applied to the under side of the shoe-body, stiffening-wires embedded side by side in the tread-body, and screws extending through said tread-body between said wires and the metal body of the shoe, said screws having wide heads which overlap engagement with the metal body to hold said tread in place, said wires in a manner to hold said screws with openings through which said screws are passed, and plugs fitting in and closing said openings.

4. An elastic-tread horseshoe comprising a metal body having a downwardly-opening recess, an elastic tread therein having a wide flat contact-surface, stiffening-wires embedded side by side in the tread-body, between said wires and having screw-threaded engagement with the metal body of the shoe, said screws having wide heads which overlap said wires in a manner to hold said tread in place.

In testimony that I claim the foregoing as my invention I affix my signature, in presence of two witnesses, this 26th day of March, A. D. 1902.

ALONZO F. KERNS.
